APPARATUS FOR FILLING CONTAINERS

Bror Anders Emil Johnson, Alsten, Sweden, assignor to Aktiebolaget Gerh. Arehns Mekaniska Verkstad, Stockholm, Sweden, a joint-stock company of Sweden

Application November 10, 1937, Serial No. 173,921
In Sweden November 14, 1936

11 Claims. (Cl. 226—119)

This invention relates to an apparatus for filling containers, preferably for filling pots with a pasty material.

It is an object of this invention to provide simple and efficient means for obtaining a thorough and homogeneous filling of containers of any customary kind and for obviating vacant spaces within the filled container and the embedment of air bubbles in the material supplied to the container.

Another object of this invention is to ensure continuous and complete filling of containers even though they might vary somewhat as to size and shape and even though the material, such as paste, might have a comparatively solid consistency.

Referring to the drawings:

Fig. 1 is an elevational view, partly in section, of an embodiment of the invention;

Fig. 2 is a vertical central longitudinal sectional view, on an enlarged scale, of the mechanism at the filling station of Fig. 1;

Fig. 3 is an elevational view, partly in section, on an enlarged scale, of the mechanism at the first smoothing station of Fig. 1;

Fig. 4 is a view in the direction IV—IV of Fig. 3;

Figs. 5, 7 and 8 illustrate some modified details of the apparatus embodying the invention;

Fig. 6 illustrates a modified embodiment of the invention.

Referring more specifically to Figs. 1 and 2, the pots 1 are conveyed upon a table 3 stepwise in the direction of the arrow (Fig. 1) by means of a chain 2 having drivers 60. First, the pots are moved into position below a filling device 4, then below a device 5 for smoothing the surface of supplied material, then possibly into position below still another device 6 for smoothing and possibly into still more such devices.

The filling device 4 has a filling pipe 7, the top end of which is connected to a device for delivering filling material. It is provided by way of example that paste is supplied intermittently to the pipe 7 by means of a pump device of the kind described and illustrated in British Patent No. 424,673. The pipe 7 is secured by means of a nut 8 within a sleeve 9 to which is secured a gear wheel 10 which meshes with a stepwise or continuously driven gear wheel 11. To the lower end of the pipe 7 is secured an exchangeable nozzle ring 12 which has channels 13. A casing 14 has a sleeve 15 that encloses the pipe 7 tightly. Furthermore, the casing 14 has a discharge pipe 16 and an annular ring 17 adapted to act as a cover

for the pots to be filled. A narrow annular space is left between the ring 12 and the cover 17. The cover 17 has an annular, elastic packing 19 that is adapted to tightly engage the rim of the pot 1. A ring 20 that serves as an abutment is secured to the sleeve 15, and another ring 21 which has a peripheral groove 21 is fitted loosely upon the said sleeve 15. A contractile spring 22 is inserted between the casing 14 and the ring 21. An arm 18 straddles the ring 21 and is secured to the upper end of a sleeve 24 which is mounted loosely on a spindle 23 that is secured to a table 33 that forms part of the frame of the apparatus. To the lower end of the sleeve 24 is secured another arm 25 through which projects a spindle 26 that has an abutment 32 and carries a pot supporting plate 27. A contractile spring 28 is inserted between the plate 27 and the arm 25. A cam disc 29 is secured to a continuously revolving shaft 62 that is driven by a mechanism that also drives the conveyor 2 and the pump for supplying paste to the pipe 7. The cam disc 29 is arranged to move the spindle 26 and plate 27 upwards towards the pipe 7 and to lower said plate again. When the plate and the pot resting thereon are being lowered, the tube 7 may be shaken. The tube 7 may be shaken by means of a lever 31 that is pivotally journaled on a shaft 63 and actuated by a cam disc 30 which is secured to an intermittently revolving shaft 64. The shaft 64 is driven by means that is operably connected to the means for driving the shaft 62, so that the shaft 64 is revolved when the spindle 26 is lowered.

When a pot 1 has been moved by the chain 2 into position upon the plate 27 the latter is moved upwards, so that the upper rim of the pot engages tightly the packing 19, whereby the spring 22 is compressed somewhat, until the shoulder 32 engages the arm 25, so that the sleeve 24 together with the arm 18 and the ring 21 are lifted. Then the casing 14 will be moved upwards by the intermediary of the pot 1 without further compressing the spring 22. Thereby, the filling spout formed by the lower end of the pipe 7 and the ring 12 will be introduced into the pot, as shown in Fig. 2. Now the pump (not shown) will force a predetermined quantity of paste out of the pipe 7 simultaneously as the pipe 7 rotates. Then the plate 27, the casing 14 and the pot 1 are lowered, whereby, under the influence of the spring 22, the packing of the cover 17 will still engage the pot tightly. The paste that is forced into the pot is pressed outwardly and fills completely any cavity within same. During the filling, air is

discharged from the pot through the narrow annular space between the ring 12 and the cover 17 as well as through the channels 13 in the ring. In order to ensure a complete and homogeneous filling of the pot, surplus paste may be forced into the pot through the pipe 1. In this case, at the end of the filling, paste will have been forced out of the pot through the channels 13 in the ring 12 and through the space between the ring and the cover 17. At the end of the filling, the lower end of the ring 12 will be at a level with the lower face of the cover 17 and, simultaneously, the arm 25 will rest upon the table 33, and the carrier plate 27 will be at a level with the table 13 which is positioned at a slightly higher level than the table 3. The pot 1 is still maintained clamped by spring pressure between the cover 17 and the plate 27. Then the conveyor chain 2 moves the filled pot aside, whereby the upper level of the paste supplied thereto is smoothed preliminarily by the cover 17. The conveyor chain moves the filled pot aside from the plate 27 onto the table 13 and thereby the pot is introduced beneath a stationary plate 65 that prevents overturning of the pot when the latter is about to leave the cover 17. Thereafter, the spindle 26 is lowered slightly, so that the plate 27 is brought into a level with the table 3. Thereby, the shoulder ring 20 is supported by the ring 21, so that the cover 17 cannot be lowered further, but then sufficient space will be obtained between the cover 17 and the plate 27 to allow another pot to be introduced between them.

The filled pot is advanced further on the table 13 into a position upon a carrier plate 49 (Figs. 1 and 3) below the smoothing device 5. Said device has a smoothing plate 34 which is engaged tightly by two scraper plates 35 each of which is secured to an arm 36. The arms 36 are pivoted to a yoke 37 that is secured to a sleeve 39, and they are urged inwards against the plate 34 by means of a tension spring 38 which interconnects them. As shown in Fig. 4, the bottom edge of the plate 34 has a contour that corresponds to the shape of the upper part of the pot. The plate 34 is secured to a spindle 40 that is movable longitudinally within the sleeve 39. A ring 41 is movable longitudinally upon the sleeve 39 and a pin 42 projects transversely through the ring 41 and two opposite longitudinal slots 43 in the sleeve as well as through the spindle 40, so that the ring 41 is secured to the spindle 40 and so that said ring can move the spindle longitudinally within the sleeve 39. An arm 4 straddles the ring 41 and is secured to a turnably journaled rock shaft 45. The sleeve 39 which is axially supported by a bearing 46 has a small pinion 47 which meshes with a larger gear wheel that is secured to a shaft 66. The shaft 66 may be operably connected to the means for driving the conveyor chain 2 so as to be rotated intermittently in timed relation to the mechanism for driving the conveyor and to the mechanism for elevating the pot 1 and operating the rock shaft 45. The carrier plate 49 is mounted on a spindle 67 which is mounted slidably in a sleeve 68. A contractile spring 69 is inserted into said sleeve and urges the plate 49 upwards, so that a pin 70, inserted transversely into the spindle 67, will rest on the sleeve 68 at the top of longitudinal slots 71 provided in the said sleeve. The mechanism for moving the plate 49 up and down has a curved disc 72 which is secured to a rotary shaft 75 which is driven by the shaft 62.

In operation, the carrier plate 49 lifts the pot 1

so that the upper rim of the latter engages the plate 34 which is rotated relatively rapidly by means of the gear 41, 48. The cam disc 72 holds the sleeve 68 for a predetermined interval at a predetermined height. When the pot 1 is pressed against the plate 34 the spring 69 is contracted slightly. Then the arm 44 slowly lifts the revolving spindle 40 and plate 34, whereby the plate 49 ascends until the pin 70 hits the sleeve 68. The arm 44 continues to lift the still revolving plate 34, so that the latter is slowly retracted from the pot 1 and an even smoothing of the upper surface of paste is obtained. Thereafter, the cam disc 72 retracts the carrier plate 49, so that the pot is lowered into a level with the table 13, whereafter the conveyor 2 moves the pot aside. When the carrier plate 49 is lowered, the smoothing plate 34 is pulled upwards between the scraper plates 35 by the arm 44, so that paste adhering to the plate 34 will be removed therefrom and stick to the plates 35. Suitably, another scraper plate 55 is connected to driving means that move said plate over both the scraper plates 35 to remove paste from them and discharge such paste into a receptacle 80. The scraper plate 55 is supported in a guide 76 and pivotally connected to a lever arm 77 that is secured to a rock shaft 78. The rock shaft is connected to a driving mechanism that is operably connected to the shaft 45 to impart to the shaft 78 a rapid reciprocating movement over the bottom face of the plates 35 when the plate 34 has been lifted, so that its lower edge is at a level with the bottom surface of the plates 35. A rod 81 is arranged to be moved up and down as well as to be reciprocated together with the plate 55. When the plate 55 has been moved over the bottom faces of the plates 35 and has obtained its end position at the receptacle 80 the rod 81 will be moved slightly upwards, so that the plate 55 is pivoted about the pin 82 and engages the receptacle 80, so that paste adhering to the plate 55 will be scraped off and dropped into the receptacle 80. The upper end of the rod 81 forms the guide 76.

In case a further device 6 is used to even the upper surface of the paste in the pot said device might suitably have a plate similar to the plate 34 but adapted to project somewhat deeper than the latter into the pot.

As shown in Fig. 5, also the cover 17 may have openings 54 for the discharge of air as well as surplus material pressed into the pot. As shown in Figs. 7 and 8, the ring 12 may have longitudinal, exterior slots that serve to discharge air and material pressed in excess into the pot. As illustrated in Fig. 6, the pot 1 to be filled may be placed in an overturned position upon a table 50 that forms a cover which engages the pot tightly and has openings 51 for discharging air and possibly also paste in excess. The filling spout that forms an end of the filling tube 1 receives and delivers portions of paste in the same manner as the other embodiment described above and serves as a support for the table 50, which may form an integral part of said spout.

Reference is made to my divisional application Serial No. 339,991, for Machine for filling containers, filed June 11, 1940, in which the combination between the features of the filling and smoothing apparatus disclosed herein is claimed.

I claim:

1. An apparatus for filling containers having filling openings comprising a cover for tightly engaging the edges of said opening of a container, said cover having an aperture for discharging air

and excess filled material from the container, a filling spout extending through the opening in said cover, and means for turning said spout and container relatively.

5. 2. An apparatus for filling containers having filling openings comprising a cover for tightly engaging the edges of said opening of a container, said cover having an opening for discharging air and excess filling material from the container, a 10 filling spout extending through said cover, a container supporting member, means for holding the container between said cover and said supporting member with yielding pressure, and means for moving the container aside to remove it laterally 15 from said cover while being subjected to the pressure of said yielding means.

3. An apparatus for filling containers having filling openings comprising a cover for tightly engaging the edges of said opening of the container, 20 said cover having an opening for discharging air and excess filling material from the container, a filling spout extending through said cover, a supporting member, means for holding the container between said cover and said supporting member 25 with yielding pressure, a guide arranged adjacent to and at a level with said cover, and means for moving the container aside to remove it laterally from said support and introducing it below said guide while being subjected to the pressure 30 of said yielding means.

4. An apparatus for filling containers having filling openings comprising a filling spout, and a cover for tightly engaging the edge of the filling opening of a container, the lower surface of said 35 cover extending at said filling opening substantially transversely to said spout and having an opening for discharging air and filled material from said container, said filling spout being adapted to project into said cover, said filling 40 spout and said cover being yieldingly, relatively displaceable longitudinally to allow said spout to enter deeply into the container while maintaining tight engagement of said cover with said edge of said filling opening and also to maintain 45 tight engagement of said cover with said edge of said filling opening when said spout and said container are withdrawn from each other until the end of said spout has reached a position substantially at a level with said lower surface of said 50 cover.

5. An apparatus for filling containers having filling openings comprising a filling spout, and a cover for tightly engaging the edge of the filling opening of a container, the lower surface of said 55 cover extending at said filling opening substantially transversely to said spout and having an opening for discharging air and filled material from said container, said filling spout being adapted to project into said cover, said filling 60 spout and said cover being yieldingly relatively displaceable longitudinally to allow said spout to enter deeply into the container while maintaining tight engagement of said cover with said edge of said filling opening and also to maintain 65 tight engagement of said cover with said edge of said filling opening when said spout and said container are withdrawn from each other until the end of said spout has reached a position substantially at a level with said lower surface of said 70 cover, said filling spout having longitudinal exterior grooves forming outlets for air and filled material from the container.

6. An apparatus for filling containers having filling openings, comprising a filling spout, means 75 for turning said spout and a container relatively,

and a cover for tightly engaging the edge of the filling opening of a container, the lower surface of said cover extending at said filling opening substantially transversely to said spout and having an opening for discharging air and filled material from said container, said filling spout being adapted to project into said cover, said filling 5 spout and said cover being yieldingly relatively displaceable longitudinally to allow said spout to enter deeply into the container while maintaining tight engagement of said cover with said edge of said filling opening and also to maintain 10 tight engagement of said cover with said edge of said filling opening when said spout and said container are withdrawn from each other until the end of said spout has reached a position substantially at a level with said lower surface of said 15 cover.

7. An apparatus for filling containers having filling openings comprising a filling spout, a cover 20 for tightly engaging the edge of the filling opening of a container, and means for shaking said spout and said cover longitudinally relatively to each other, the lower surface of said cover extending at said filling opening substantially 25 transversely to said spout and having an opening for discharging air and filled material from said container, said filling spout being adapted to project into said cover, said filling spout and said cover being yieldingly relatively displaceable 30 longitudinally to allow said spout to enter deeply into the container while maintaining tight engagement of said cover with said edge of said filling opening and also to maintain 35 tight engagement of said cover with said edge of said filling opening when said spout and said container are withdrawn from each other until the end of said spout has reached a position substantially at a level with said lower surface of said 40 cover.

8. An apparatus for filling containers having filling openings comprising a filling spout, a cover for tightly engaging the edge of the filling opening of a container, the lower surface of said cover extending at said filling opening substantially 45 transversely to said spout and having an opening for discharging air and filled material from said container, said filling spout being adapted to project into said cover, said filling spout and said cover being yieldingly relatively displaceable 50 longitudinally to allow said spout to enter deeply into the container while maintaining tight engagement of said cover with said edge of said filling opening and also to maintain 55 tight engagement of said cover with said edge of said filling opening when said spout and said container are withdrawn from each other until the end of said spout has reached a position substantially at a level with said lower surface of said cover, means for supporting the container, a guide positioned adjacent to said supporting means, and means for displacing the container laterally from its position between said cover and said supporting means, said guide serving to prevent tilting of the container when the container is being removed 60 from said cover.

9. An apparatus for filling containers having filling openings comprising a filling spout, and a cover for tightly engaging the edge of the filling opening of a container, said cover having an 70 opening therein for discharging air and filled material from said container, a filling spout introduced in spaced relationship through said opening of said cover, the lower surface of said cover at said opening extending substantially 75

transversely to said spout, said filling spout and said cover being yieldingly relatively displaceable longitudinally to allow said spout to enter deeply into the container while maintaining tight engagement of said cover with said edge of said filling opening and also to maintain tight engagement of said cover with said edge of said filling opening when said spout and said container are withdrawn from each other until the end of said spout is substantially at a level with said lower surface of said cover.

10. An apparatus for filling containers having filling openings comprising a filling spout, and a cover for tightly engaging the edge of the filling opening of a container, said cover having an opening therein for discharging air and filled material from said container, a filling spout introduced in spaced relationship through said opening of said cover, the lower surface of said cover at said opening extending substantially transversely to said spout, said filling spout and said cover being yieldingly relatively displaceable longitudinally to allow said spout to enter deeply into the container while maintaining tight engagement of said cover with said edge of said filling opening and also to maintain tight engagement of said cover with said edge of said filling opening when said spout and said container are withdrawn from each other until the end of said spout is substantially at a level with said lower surface of said cover, said spout having at its end a lateral annular extension of sub-

stantially the same width as the width of said opening of said cover, said extension substantially closing said opening of said cover when the spout projects slightly beneath said cover.

11. An apparatus for filling containers having filling openings comprising a filling spout, and a cover for tightly engaging the edge of the filling opening of a container, said cover having an opening therein for discharging air and filled material from said container, a filling spout introduced in spaced relationship through said opening of said cover, the lower surface of said cover at said opening extending substantially transversely to said spout, said filling spout and said cover being yieldingly relatively displaceable longitudinally to allow said spout to enter deeply into the container while maintaining tight engagement of said cover with said edge of said filling opening and also to maintain tight engagement of said cover with said edge of said filling opening when said spout and said container are withdrawn from each other until the end of said spout is substantially at a level with said lower surface of said cover, said spout having at its end a lateral annular extension of substantially the same width as the width of said opening of said cover, said extension substantially closing said opening of said cover when the spout projects slightly beneath said cover, said annular extension being tapered at its top end.

BROR ANDERS EMIL JOHNSON.
